UNITED STATES PATENT OFFICE.

EDWIN S. FAULKNER, OF CHICAGO, ILLINOIS.

DESIGN FOR A BIRD HOUSE.

Application filed March 3, 1928. Serial No. 25,662. Term of patent 14 years.

To all whom it may concern:

Be it known that I, EDWIN S. FAULKNER, a citizen of the United States, residing at Chicago, in the county of Cook and State of Illinois, have invented a new, original, and ornamental Design for Bird Houses, of which the following is a specification, reference being had to the accompanying drawing, forming part thereof.

Figure 1 is a perspective view of a bird house showing my new design;

Fig. 2 is a front elevation thereof; and

Fig. 3 is a rear elevation thereof.

I claim:

An ornamental design for a bird house, as shown.

EDWIN S. FAULKNER.
